FLASH LIGHT

Joseph F. Moran, Waterbury, Conn., assignor to
Scovill Manufacturing Company, Waterbury,
Conn., a corporation of Connecticut

Application October 26, 1933, Serial No. 695,219

2 Claims. (Cl. 240—10.68)

This invention relates to flashlights, and more particularly to an improved lock switch for controlling the circuit through the flashlight bulb.

One object of this invention is to provide a lock switch of the above nature comprising only a pair of elements mounted on the side of the flashlight casing, and having means whereby the light may be intermittently flashed or latched in closed-circuit position to produce a continuous light.

A further object is to provide a lock switch mechanism of the above nature which is provided with a sliding thumb piece which may be locked in open-circuit position to prevent accidental closing of the switch.

A further object is to provide a flashlight casing having novel means for positioning the center terminal of the battery in alignment with the lower terminal of the lamp, and also serving to keep the batteries out of engagement with the switch mechanism.

A further object is to provide a device of the above nature which will be simple in construction, inexpensive to manufacture, easy to assemble and manipulate, compact, ornamental in appearance, and very efficient and durable in use.

With these and other objects in view there have been illustrated on the accompanying drawing, two forms in which the invention may be conveniently embodied in practice.

In the drawing:

Fig. 1 represents an elevation of a flashlight with parts broken away on a longitudinal section to show the interior construction, with the switch in locked open-circuit position.

Fig. 2 is a similar fragmentary longitudinal section of the same showing the switch held "latched" in prolonged closed-circuit position.

Fig. 3 is a face view of the switch mechanism.

Fig. 4 is a similar view of the same with the sliding thumb-piece removed.

Fig. 5 is a plan view of the head end of the flashlight, with the head assembly and lamp bulb removed.

Fig. 6 is a transverse sectional view taken through the switch mechanism along the line 6—6 of Fig. 1.

Fig. 7 is a detail perspective view of a modified form of conductor ring combined with a pair of integral battery guard members.

Referring now to the drawing in which like reference numerals denote corresponding parts throughout the several views, the numeral 10 indicates a sheet metal casing having an en-

larged threaded forward end 11 for detachably receiving a head shell 12, the latter being provided with an inturned annular shoulder 13 and a peripheral octagonal nut section 14. The head shell 12 is provided with the usual flat glass lens 15 positioned between the shoulder 13 and the flanged forward rim 16 of a parabolic reflector 17, which is held in place by means of a four-sided spring wire spider member 18 of common construction, having detachable engagement in the points of the octagonal nut section 14 of said head shell 12. It is to be understood that this construction allows the head shell 12, the lens 15, and the reflector 17 to be removed from the casing 10 as a unit. Moreover, by reason of the threaded engagement of the head shell 12 upon the enlarged threaded end 11 of the casing, the reflector 17 may be readily focused with respect to a lamp bulb 19.

The bulb 19 is mounted in a threaded metallic socket 20 located at the center of an insulation block or disc 21, preferably of octagonal shape, and adapted to seat within a flared-octagonal neck section 22 joining the main part of the casing 10 with the enlarged end 11 (see Figs. 1 and 5). A metallic conductor ring 23 is positioned on the inside surface of the insulation block 21 and is adapted to be secured to said block by the spun-over bottom end 24 of the metallic socket 20. The conductor ring 23 has an outwardly extending arm 23a provided with a turned-up lug 25 lying within a slot 26 formed in one side of the octagonal block 21, said lug 25 serving as the stationary contact of the switch, and adapted to be engaged by a movable elongated contactor strip 27 forming a part of the switch mechanism to be more fully described later.

The socket 20 is provided with the usual enlarged opening 28 at its base for surrounding the inner terminal 29 of the lamp 19, said terminal being adapted to contact directly with the upper terminal 30 of the upper cell 31 of the battery. In order to assure that the upper terminal 30 will always remain in good electrical contact with the lower lamp terminal 29, provision is made of a circular guard member 32 depending from the underside of the insulation block 21 to which it is secured, as by a plurality of lugs 33 projecting through corresponding slots 34, and bent over against the upper face of said block (see Fig. 5). The guard member 32 embraces the upper part of the top cell 31 except for a wide vertical cut-out slot 35 formed in said guard member in alignment with the lug 55.

25 to provide a suitable working clearance for the movable contactor strip 27. The lower edge 36 of the guard member 32 is flared outwardly into frictional engagement with the cylindrical inner wall of the casing 10, whereby said guard member will be held rigidly in position.

6 by the lower edge of the finger opening 42 in the thumb-piece 40. In order to unlock the thumb-piece 40 to permit the prolonged closing of the switch, it will first be necessary to depress the push-button 45 sufficiently to clear the lower 5 edge of the opening 42.

For the purpose of guiding the contactor strip 37 in its circuit closing and opening movements, and also holding the adjacent cell of the battery away from said strip, provision is made of a pair 10 of inturned lugs 48, 48 formed integral with the escutcheon plate 37 along opposite sides of the longitudinal edge of the central opening 38 thereof, said lugs being adapted to straddle the push-button section 45 of said contactor strip 27. 15

10 The mechanism for causing the contactor strip 27 to move into engagement with the lug 25 comprises a rectangular escutcheon plate 37 preferably formed integral with the casing 10, and having a rectangular central opening 38 spaced from the four corners of which are a plurality of longitudinal slots 39, as shown in Fig. 4. 15 An exterior sliding thumb-piece 40 is adapted to overlie the plate 37 and is provided with a pair of longitudinally spaced opposed stepped sections 41, 41a, between which is a central finger opening 42. The thumb-piece is held in position on the escutcheon plate 37 by means of four ears 43, extending through the slots 39 and engaging the under surface of said plate 37.

15 The contactor strip 27, previously referred to, extends longitudinally along the interior wall of the casing 10 in alinement with said openings 38 and 42, and is rigidly secured at its lower end to the casing 10, as by a tubular eyelet rivet 44. The intermediate portion of the strip 27 is provided with an outwardly offset integral section 45, comprising a push-button which is adapted to project through the opening 38 in the escutcheon plate 37 and the opening 42 in the thumb piece 40. The push-button 45 is adapted to lie substantially flush with the upper portion of the thumb-piece 40 when the lamp circuit is open (see Fig. 1). It will thus be seen that, when the push-button 45 is depressed, the upper free end of said strip 27 will move into contact with the lug 25 on the conductor ring 23 for closing the electrical circuit through the lamp bulb 19. Electrical connection is established to the bottom terminal of the battery by means of the casing 10 and the bottom screw cap 47.

20 When the parts are in the position shown in Fig. 1, the lamp may be flashed on momentarily and will remain lighted so long as the operator pushes inwardly with his finger upon the push-button 45. When he removes his finger, the resiliency of the elongated contactor strip 27 will automatically swing said strip away from the stationary contact 25, thus opening the circuit and extinguishing the lamp bulb 19. When, 25 however, it is desired to hold the switch in closed circuit position for a longer period, without the necessity of pressing upon the push button, it will only be necessary to press the push-button inwardly while the thumb-piece 40 is being pushed upwardly to the position shown in Fig. 2, whereby the lower stepped section 41a will engage the push-button 45, and will hold it inwardly with the strip 27 in prolonged closed-circuit position as long as desired.

30 It will be understood that the switch may then be readily restored to open-circuit position merely by sliding the thumb-piece 40 downwardly to its original position shown in Fig. 1.

35 An important feature of the present invention is that, when the switch parts are in the open-circuit position, as shown in Fig. 1, the thumb-piece 40 will be positively locked against accidental sliding movement to close the switch by reason of the engagement of the push-button

20 In the modified form of the invention shown in Fig. 7, the conductor ring and guard sections are made in one unit 49 comprising a semi-circular apertured section 50, a broad lateral projection 51, and a pair of depending spaced guard 25 lugs 52, 52 integral therewith. The apertured section 50 is adapted to be attached to the insulation block 51 by means of the bulb socket 20 in the same manner as in the first form shown in Figs. 1 and 2.

25 A short upstanding terminal lug 53 is integrally formed on the edge of the projection 51 between the depending lugs 52, 52, and when the unit 49 is assembled to the insulating block 21, said lug 53 will be disposed within the slot 30 26 in alinement with the movable contactor strip 27 by which it is adapted to be engaged for completing the circuit.

30 While there have been disclosed in this specification two forms in which the invention may 35 be embodied, it is to be understood that these forms are shown for the purpose of illustration only, and that the invention is not to be limited to the specific disclosures but may be modified and embodied in various other forms without 40 departing from its spirit. In short, the invention includes all the modifications and embodiments coming within the scope of the following claims.

35 Having thus fully described the invention, 45 what is claimed as new, and for which it is desired to secure Letters Patent, is:

1. In a flashlight, a battery casing, an insulating lamp socket supporting block at the top 50 of said casing, a stationary contact spaced inwardly of said casing and electrically connected with said socket, a longitudinal movable contact located within said casing in alinement with said stationary contact, means on the exterior of said casing for operating said movable contact, said block having a depending tubular 55 guard member to prevent said battery from engaging said movable contact.

2. In a flashlight, a battery casing, an insulating lamp socket supporting block at the top 60 of said casing, a stationary contact spaced inwardly of said casing and electrically connected with said socket, a longitudinal movable contact located within said casing in alinement with said stationary contact, means on the exterior 65 of said casing for operating said movable contact, said block having a depending tubular guard member to prevent said battery from engaging said movable contact, said guard having a vertical slot in alinement with said movable contact to permit free movement thereof into contact with said stationary contact.

JOSEPH F. MORAN.
